UNITED STATES PATENT OFFICE.

WILLIAM H. HALL, OF CINCINNATI, OHIO, AND JOHN E. DWYER, OF NEWPORT, KENTUCKY, ASSIGNORS TO THE HALL'S SAFE COMPANY, OF CINCINNATI, OHIO, A CORPORATION OF OHIO.

SAFE.

964,861.

Specification of Letters Patent. Patented July 19, 1910.

Original application filed June 1, 1909, Serial No. 499,467. Divided and this application filed April 5, 1910. Serial No. 553,647.

To all whom it may concern:

Be it known that we, WILLIAM H. HALL and JOHN E. DWYER, residing, respectively, at Cincinnati, in the county of Hamilton and State of Ohio, and at Newport, in the county of Campbell and State of Kentucky, have jointly invented certain new and useful Improvements in Safes, of which the following is a specification.

10 This application is a division of our application for patent on improvements in safes, filed June 1, 1909, Serial No. 499,467, to which reference is hereby made.

Our invention relates to safes, especially 15 to the character of safes known as burglar-proof safes, and has for its object the provision of means for retarding ingress to the interior of the safe, while permitting ready treatment of the door of the safe and its 20 convenient assembling.

Our invention is designed primarily for application to so-called manganese safes, the material whereof has been subjected to a manganese process or treatment which renders the metal especially tough and hard, resulting in difficulty or impossibility in machining the metal thereof by means of metal tools, but it is obvious that the same may be applied to safes of different or other 25 material.

In practice, in the process of treatment of the metal for producing manganese safes, the depth below the surface of the metal to which the hardening and toughening process 30 reaches is limited, this depth being at present about one and a half inches. In our improved device we provide a door having an inner member and an outer member spaced apart and so arranged that they may 35 be connected after treatment, thus enabling the adjacent walls of the door-members to be subjected to the direct action of the treatment for producing members of great ingress-resisting qualities.

40 The invention will be further readily understood from the following description and claims, and from the drawings, in which latter:

Figure 1 is an axial section of our improved device taken on a line corresponding to the line $z-z$ of Fig. 2, the body of the safe being partly broken away. Fig. 2 is a vertical section of the same taken on a line corresponding to the line $y-y$ of Fig. 1.

Fig. 3 is a similar section of the same on a line corresponding to the line $x-x$ of Fig. 1. Fig. 4 is a detail in cross-section on the line $w-w$ of Fig. 2. Fig. 5 is a similar detail on the line $v-v$ of Fig. 2. Fig. 6 is a cross-section of our improved device taken on the irregular line $u-u$ of Fig. 2. Fig. 7 is a detail in front elevation showing the position of the combination-lock. Fig. 8 is a detail in cross-section on the line $t-t$ of Fig. 2, but showing a modified form of joint for the connecting-members; and, Fig. 9 is a perspective view of one of the connecting-blocks having a modified form of joint thereon.

1 represents the body of the safe and 2 the door thereof. The door comprises an inner member 3 and an outer member 4. The body and the inner and outer door-members are preferably composed of manganese or other treated steel for producing an especially hard and tough texture which 75 is not responsive to the action of drills or other metal tools and which we shall hereinafter refer to as treated metal.

In a safe, the door is the part most vulnerable to attack by burglars and in order to 80 provide a door as nearly invulnerable as possible, we have provided an outer member which is separated from the inner member so that the door may be subjected to the treatment not only at the inner and outer 85 faces of the door, but also subjected to the direct treatment at the adjacent faces of its members. Thus the outer member is provided with an outer face 5 and an inner face 6 and the inner member is provided with an 90 outer face 7 and an inner face 8, the inner face 6 of the outer member and the outer face 7 of the inner member being adjacent faces, which are spaced apart, as indicated by the space 9, between the same.

95 The door-members, being subjected to treatment as stated, are rendered practically invulnerable to the action of metal tools, and we therefore prefer to provide connecting means between said members of material 100 other than said treated material, which is capable of being acted on by metal tools for producing economy in manufacture and an article of superior proof against burglarizing, the connecting means being located between the door-members. These connecting means are shown as comprising interlocking joints 10.

We prefer that the connecting means between the inner and outer door-members shall be made of material other than the treated material of which said door-members are composed and to provide said door-members with inserts of material other than the treated material of which said door-members are composed, and to secure the connecting-means between the door-members 5 to said inserts, these connecting-means and inserts being of a material which is susceptible to action by metal tools, for instance tool-steel.

In the preferred form of our improved device, the inner door-member is provided with blocks 12 which may have connecting webs 13 and a connecting web 14 between the same, there being recesses 15 16 between said blocks. The outer surface of the inner door-member has inserts 17 in the same, these inserts being of greater cross-section at their embedded portion than at their outer ends, instanced by enlargements 18, for preventing the withdrawal of said inserts from said inner door-member. Screws 19 connect the blocks 12 with the inserts 17, the bolts being threaded into internally threaded sockets 20 in said inserts.

The inner face of the outer door-member 30 is provided with blocks 21 having recesses 22 23 between them. For securing the blocks 21 to the outer door-member we provide the inner face of the latter with inserts 24 which also have enlargements as shown at 25 embedded in said outer door-member for preventing the disengagement of said inserts. Screws 26 connect the blocks 21 with said inserts. The metal of the door-members is cast about the inserts.

40 The blocks on the door-members in one form of construction which we have shown, (see Figs. 1 and 5), respectively have mating faces shown at tapered under-cut or dove-tail faces. These faces are shown as 45 comprising tapering portions 29 and shoulders 30, the tapering portions insuring firm approach between the door-members when connecting the same, and said shoulders limiting said approach and preventing tilting said approach and preventing tilting 50 of the outer upon the inner door-member. The faces respectively on the inner and outer door-members with which said blocks are arranged to contact are preferably fitted by grinding by means of emery-wheel or the like.

55 In another form of construction which we have shown, (see Figs. 8 and 9), the blocks 12 21 between the door-members have mating faces 33, shown as serrated in cross-section, the serrations extending parallel to each other and to the side-faces of said blocks. Other forms of joints may also be provided. The blocks 12 21 form connecting members between said door-members, and 60 are arranged in pairs. In assembling the

door-members, they are so positioned that the blocks 12 and 21 of the respective pairs of said connecting members are out of radial line with each other, whereupon respective turning is caused between the door-members 70 for bringing said blocks of said respective pairs of connecting members into coincident radial positions, and thereby causing relative sliding movement between the adjacent faces of said blocks.

75 34 are positioning blocks arranged to span the joints between the connecting members on the respective door-members for preventing relative turning of the door-members, the positioning-blocks being received in the 80 recesses 15 22. The adjacent end-walls 35 36 of the connecting-blocks are preferably convergingly tapered, the ends 37 of the positioning blocks 34 being similarly tapered. Screws 38 are received in threaded apertures 39 in the connecting webs 13 and are arranged to draw the positioning blocks 34 85 between the converging adjacent end-faces of the connecting members for locking the inner and outer door-members securely in 90 relative positions.

The door-opening comprises an outer tapered wall 40 and an inner tapered wall 41, separated by an annular shoulder 42. The outer door-member has a tapered periphery 43, which fits the outer tapered wall 40, while the inner peripheral edge 44 thereof is arranged to engage the shoulder 42 when the door is closed. The inner door-member has a tapered periphery 45 which is 95 arranged to fit the inner tapered wall 41, and said inner door-member is arranged to enter said inner tapered wall so as to be spaced from said shoulder a distance corresponding to the distance between said inner 100 and outer door-members, whereby the result is obtained that even if said outer door-member should be blown off, the safe is still closed by the inner door-member.

105 There is a suitable combination lock 51 110 which is located in the space between the inner and outer door-members at one side thereof. The bolt 52 of said lock enters an aperture in the door-jamb in usual manner, and is used as a day-lock, and is operated 115 by a knob 53 outside the outer door-member. A time-lock 54 is located centrally at the inside of the inner door-member, the bolts 55 whereof also enter suitable apertures in the door-jamb, in usual manner, there being 120 however preferably no connection between the time-lock or its mechanism and the outside of the inner door-member, this inner door-member being preferably imperforate within the longitudinal projections of the 125 inner walls of the connecting blocks between said door-members. The space between said door-members is increased by a recess 56 in the under face of said outer door-member for accommodating said lock 51.

The combination-lock 51 has an outer bar 63 comprising laterally extending wings 64 overlapping the adjacent ends of the connecting members adjacent thereto, screws 5 65 passing through said wings and into said connecting members, securing said lock 51 in place.

There is a central space 69 between the connecting members which is in axial plane 10 with the time-lock 54. A strip 70 of the height of the space between the door-members is received about the inner end of the combination-lock 51 and connects with the ends of the connecting members which are 15 adjacent to said lock. The space between the door-members and within the connecting members and strip 70 may, if desired, be filled with a filling 71, which is a non-conductor, or substantially so, of heat or 20 electricity, for instance a hydraulic cement mixture. The filling 71 may be introduced into said space through an aperture 72 in the web 14 for filling the middle space 69.

The inner end of the inner door-member is 25 provided with lugs 79 and the wall of the door-opening is provided with lugs 80. These lugs are relatively in different positions radially of the door when said door is ready for being opened or closed, but 30 when the door is locked, the lugs respectively on the door and wall of the door-opening are brought into similar radial positions, the door being turned by suitable mechanism, not shown because well known, 35 for bringing the lugs on the door behind the lugs in the wall of the door-opening, the lugs in the wall of the door-opening being received in an annular recess 81 in the peripheral face of the inner door-member.

40 Our improved construction permits the connection between the inner and outer door-members to be made of such strength relatively to the door-members that the connection will give way prior to collapse of the 45 inner door-member or its inner locking mechanism, while it permits this connection to be made of the desired strength for its purposes.

Having thus fully described our invention, what we claim as new and desire to 50 secure by Letters Patent is:

1. In combination, a round safe-door comprising inner and outer door-members, connecting-pieces secured to the opposing faces 55 of said door-members spacing said door-members apart and forming a central filling-space therebetween, there being a filling-channel between said central filling-space and the periphery of said door, a non-conducting filling of the character described 60 in said central filling-space received through said filling-channel, the said inner door-member being imperforate within the longitudinal projection of said central filling-space, and a time-lock secured to the inner

end of said inner door-member and separated from said filling-space by said imperforate portion of said inner door-member and from said outer door-member by said non-conducting filling and imperforate portion of said inner door-member, the said non-conducting filling, imperforate portion of said inner door-member and time-lock being located in positions coincident with the rotary axis of said door, substantially as 75 and for the purpose described.

2. In a safe-door, the combination of inner and outer separate door-members composed of treated metal and spaced apart, inserts located in the adjacent faces of said 80 door-members, and connecting means between said door-members comprising pairs of mating arc-pieces rigidly connected to said inserts, the arc-pieces on the respective door-members arranged to be placed in different radial positions to locate said arc-pieces for mating connection and arranged to be brought into mating connection by relative turning between said door-members 85 for bringing said arc-pieces of said pairs of arc-pieces into coinciding radial positions, and a positioning-block received between said pairs of arc-pieces for rigidly positioning said door-members relatively to each other, substantially as described. 90

3. In a safe-door, the combination of separate inner and outer door-members spaced apart, connecting-means between said door-members located in the space between said door-members, said connecting means arranged in pairs and comprising inner and outer mating arc-pieces, the said outer arc-pieces being on one of said door-members and the said inner arc-pieces being on the other of said door-members, the said inner 105 arc-pieces being provided with connecting webs, the inner and outer arc-pieces of said respective pairs of arc-pieces being provided with mating faces projecting into each other's planes, and arranged to be brought 110 into mating relation by relative turning between said door-members, and positioning-blocks between said pairs of arc-pieces having connection with said connecting webs, substantially as described. 115

4. In a safe-door, the combination of separate inner and outer door-members having a space therebetween, mating connecting-blocks for said door-members between said door-members in said space having mating 120 faces, said connecting blocks arranged in pairs, the mating faces of the connecting blocks of one of said door-members projecting under the mating faces of the connecting blocks of the other of said door-members 125 and arranged to be inter-engaged by relative turning between said door-members, the ends of adjacent pairs of mating blocks being relatively tapered, and a positioning-block between said ends having similarly tapered 130

ends arranged to contact the said tapered ends of said adjacent pairs of said mating blocks, and said positioning-block spanning the joint between the said pairs of mating blocks, substantially as described.

5. In a safe-door, the combination of separate inner and outer door-members spaced apart, connecting members for connecting said door-members in said space between 10 said door-members and comprising inner and outer connecting-members, said connecting members having mating faces between them brought into mating relation by relative turning between said door-members, a combination-lock located in said space between 15

said door-members and between portions of said connecting-members, and provided with laterally extending wings overlapping said last-named connecting-members, and securing means between said wings and last- 20 named connecting-members, substantially as described.

In testimony whereof, we have signed our names hereto in the presence of two subscribing witnesses.
